William W. Stevens, of Portland, Maine.
Assignor to
A. P. Richardson & Co., of same place.
Letters Patent No 1200, dated Feb. 14, 1860.

The schedule referred to in these ^{drawings} Letters Patent and making part of the same.

To all whom it may concern:

Be it known that I, William W. Stevens, of the City of Portland, County of Cumberland, and State of Maine, have invented a new and ornamental Design for a Cooking Stove (which I term 'The Matchless'), and I do hereby declare that the following is a full and exact description of the same, reference being had to the accompanying drawings and to the letters of reference thereon.

Of the said drawings,

Figure 1. denotes a perspective elevation of my design and exhibits the top, front, side and hearth of the Stove, with their doors, also the legs.

Figure 2. represents a vertical section of the top A side B door C.

Des 1200

taken through the line D.E.

Figure 3, represents a vertical section of the top A, front F, front door G, hearth H, taken through the line K.L.

In said drawings C.C, represent the doors of the oven, P, represents the side door or end door of the fire box, Q.R, represent the front doors, S.S, represents the legs of the Stove.

I claim the configurations and ornaments above described and shown in the drawings as a design for a Cooking stove.

In testimony whereof I have hereunto set my hand and seal this thirty first day of December A.D. 1850.

Witnesses. {
